Filed July 30, 1965, Ser. No. 86,365

Term of patent 14 years

(Cl. D81—10)

FIG. 1.

FIG. 2.

FIG. 4.

FIG. 3.

FIG. 5.

FIGURE 1 is a top perspective view of a combined log lighter and burner tube, showing our new design.

FIGURE 2 is a bottom perspective view of the combined log lighter and burner tube shown in FIGURE 1.

FIGURE 3 is a side elevation of the combined log lighter and burner tube shown in FIGURE 1.

FIGURE 4 is an end elevation taken from the left-hand side of FIGURE 1.

FIGURE 5 is a top plan view of the combined log lighter shown in FIGURE 1.

The burner tube is broken away in FIGS. 1, 2 and 3 to indicate indeterminate length, and a portion thereof is omitted in FIG. 5 for the convenience of illustration only.

We claim:

The ornamental design for a combined log lighter and burner tube, substantially as shown and described.
